UNITED STATES PATENT OFFICE.

ERNEST A. LLEWELLYN AND NEAL D. LEACH, OF WILTON, MAINE, ASSIGNEES TO G. H. BASS & COMPANY, OF WILTON, MAINE, A CORPORATION OF MAINE.

MOCCASIN.

Application filed November 30, 1925. Serial No. 72,151.

This invention relates to foot wear and more particularly to moccasins or shoe packs.

It has heretofore been the practice in moccasin or shoe pack manufacture to join the vamp and toe-piece or top portion of the upper by means of a hand or butt seam in which the toe-piece and vamp are opposingly skived, butted with outwardly turned edges and sewed together by stitches passed intermediately through said butted edges, so as to show upon the outer surface of the vamp and toe-piece alike and giving an appearance of double stitching. This form of butt seam has proven to be neither strong nor tight, and apart from the liability to rip, the seam is liable to open up on either side so as to permit the entrance of dirt from without and moisture from within to find access to the threads of the hand or butt seam.

The objects of our invention are to provide a moccasin having a toe-piece attached thereto by a hand seam in such manner as to insure a strong and durable water-proof connection between the vamp and the toe-piece that will effectually resist the tendency of the seam to open up under pressure and permit water and dirt to enter from the outside or moisture from within to find access to the threads in said seam, and to reinforce and strengthen said seam by a second seam through the vamp and a lapped portion of the toe-piece so concealed that the lap is not visible and does not present any surface projection which is liable to be scuffed off in service by contact with any obstacle and which is also objectionable in appearance, and its elimination renders the moccasin or shoe neater and more attractive in appearance than prior constructions with exposed lap seams.

The invention will first be hereinafter more particularly described, with reference to the accompanying drawings, which are to be taken as a part of this specification, and then pointed out in the claims at the end of the description.

In said drawings, Fig. 1 is a perspective view of a moccasin constructed in accordance with our invention;

Fig. 2 is a vertical sectional view of a broken away portion of a vamp and toe-piece with the beveled edges of the two parts secured together by a single seam; the free

edge of the toe-piece being extended on the interior of the moccasin so as to provide a concealed lap to be secured to the vamp by a second seam;

Fig. 3 is a vertical transverse section taken on the line 3—3 of Fig. 1;

Fig. 4 is a detail sectional view illustrating the method of skiving the adjacent edges of the vamp and toe-piece of a moccasin as heretofore constructed; and

Fig. 5 is a detail sectional view illustrating the method of skiving the adjacent edges of the vamp and toe-piece of a moccasin constructed in accordance with our invention.

Referring to the drawings, the shoe or moccasin is shown with the vamp 4 and a top or toe-piece 5 cut to a size sufficient for its toe forming edge to continuously underlie the adjacent toe forming edge of the vamp piece, said toe-piece in this instance providing the entire upper of the shoe. The meeting edges of the vamp and toe-piece, that is, the edges of the pieces which are intended to be sewn and secured together are shown correspondingly or complementarily skived or beveled at an oblique angle to a horizontal plane, such skiving of the toe-piece around or along the toe forming edge being extended to provide a tapering buttressing apron or flap 5^a which underlies the adjacent edge of the vamp piece while the contiguous toe forming edge of the latter is more sharply and less extensively skived at substantially the same angle to provide a complementary butting edge 4^a inversely disposed thereto. The vamp and top portions are next placed upon a last and the vamp is then gathered or drawn in and slightly buckled against the top portion or toe-piece, whereupon it is sewn securely to the latter by through stitching 6, that is, the toe-piece and vamp, after being properly skived, are mutually extended or outwardly buckled against each other for the stitching

operation in which the stitches are passed transversely through the meeting skived edges of vamp and toe-piece, thus giving a neat and symmetrical appearance to the seamed joint therebetween; such stitching with respect to the toe-piece being effected at the thickest point of its edge or at a point somewhat remote from the thinner portion of said edge, so as to leave an extended or greater portion of the tapered edge providing the apron or flap 5^a to underlie the

aforesaid seam and an adjacent portion of the vamp. It will be noted that the stitching 6 does not penetrate or pass entirely through the toe-piece from its outer to its inner surface, but only from its outer surface to and through its skived edge, thus leaving the inner surface unmarred and unpierced, and the apron or flap portion 5^a covers and conceals the joint and the threads 10 of the seam on the inside of the moccasin so that moisture from the outside cannot pass along the thread to the inside of the shoe, as would otherwise result from the well known tendency of the thread to carry moisture, 15 and the threads are also unexposed to moisture from within. The advantages of such a joint and seam in this respect are obvious. The two parts having been firmly united by the single seam, there remains free and un- 20 attached a tapering or extended lower marginal portion of said toe-piece forming the flap 5^a which projects over the lower or inner skived edge of the vamp and over the lower portion of the stitching 6 on the in- 25 side, and the free edge of this flap is se- cured to the vamp by a second seam 6^a. The second seam is preferably sewed with a ma- chine using a waxed thread and a lock 30 stitch, but may be sewn by other types of machines or by hand. It will be hereinafter referred to as the second or machine seam.

The described construction has the following points of advantage: At the hand seam connecting the vamp and toe-piece, the meet- 35 ing edges of each are skived or beveled at substantially the same angle, and their op- 40 posing surfaces therefore lie naturally in full contact with each other, and the seam thus formed is strong and tight, effectively 45 resisting pressure to open the seam up whether applied from the outside or inside. The second or machine seam reinforces and strengthens the hand seam, first in resisting a direct pull at right angles to the line of 50 the seam, and second in holding the gathered fullness (pucker) of the vamp securely to the projecting flap of the toe-piece and thereby entirely relieving the hand seam from the strain of holding the pucker of the 55 vamp, which strain being in the nature of a shear is a serious cause of ripping of the ordinary hand seam. The downward project- 60 ing flap on the toe-piece when stitched to the vamp by the second seam effectively 65 closes any possible opening in the hand seam, thus making it impossible for dirt, dust or water entering at the hand seam to reach the foot, and also impossible for any per- 70 spiration or other moisture from the inside to

reach the thread of the hand seam. The 60 downwardly and inwardly projecting flap on the toe-piece, being on the inside of the vamp, is protected from wear when the moccasin is scuffed against brush or other ob- 65 stacles; this being a serious source of trouble on overlapping toe-pieces as we have learned by experiment and experience, and being out of sight it gives the moccasin a much trim- 70 mer and neater appearance.

Having thus described our invention, 70 what we claim as new and desire to secure by Letters Patent of the United States is:

1. A moccasin comprising a toe-piece and a vamp having the meeting edges thereof skived or beveled so as to present inclined 75 surfaces extending along substantially parallel lines at an angle to a horizontal plane; said toe-piece and vamp being gathered and secured together by a seam or row of stitches passing through the marginal portions or 80 meeting edges thereof from the upper outer side of the toe-piece to a point below the upper outer edge of the vamp; said toe-piece having a reduced downwardly projecting extension forming a flap which underlies 85 said stitches and the joint between said meeting edges and is concealed on the inner side of the vamp and secured thereto by a lap seam reinforcing the first named seam.

2. A moccasin comprising a toe-piece and a vamp having the meeting edges thereof skived or beveled so as to present inclined 90 surfaces extending along substantially parallel lines at an angle to a horizontal plane; said toe-piece and vamp being gathered and 95 secured together by a seam or row of stitches passing through the marginal portions or meeting edges thereof from the up- 100 per outer side of the toe-piece to a point be- 105 low the upper outer edge of the vamp; the edge of the toe-piece being extended down- 110 wardly and inwardly so as to overlap the joint and protect said seam on the inner side of the moccasin; the said edge being secured to the vamp by a lap-seam reinforcing the first named seam, and said surfaces thus joined together extending the full length of the inclined edge of the vamp along substan- 115 tially parallel lines in approximately a ver- 120 tical plane and without leaving any projec- 125 tion on the outer side of the moccasin that may be scuffed off and producing an attrac- 130 tive and finished appearance.

In testimony whereof we affix our signatures.

ERNEST A. LLEWELLYN.
